UNITED STATES PATENT OFFICE.

JAMES D. HUMPHREY, OF TOWANDA, PENNSYLVANIA.

NUMBERING AND STAMPING MACHINE.

No. 817,429.

Specification of Letters Patent.

Patented April 10, 1906.

Application filed May 5, 1905. Serial No. 253,987.

To all whom it may concern:

Be it known that I, JAMES D. HUMPHREY, a citizen of the United States, residing at Towanda, in the county of Bradford and State 5 of Pennsylvania, have invented certain new and useful Improvements in Numbering and Stamping Machines, of which the following is a specification.

My invention has relation to a power numbering and stamping machine; and in such 10 connection it relates more particularly to the construction and arrangement of the same.

The principal objects of my invention are, first, to provide a balanced type-head requiring 15 little power for its proper operation and to render it readily interchangeable by the manner of its support and its connection with a driving mechanism; second, to so arrange the driving mechanism for the type-head as to impart to the same movements of 20 varying lengths to bring the type-head alternately into engagement with an inking-pad and then into engagement with an article which is to be numbered, stamped, or marked; third, to provide the driving mechanism with means to impart a reciprocatory 25 movement to the inking-pad to shift the same alternately into and out of the path of the type-head; fourth, to provide an adjustable 30 inking-pad holder and to adapt the same for the reception of inking-pads of varying sizes, and, fifth, to provide a yielding and adjustable table upon which the article to be marked is placed.

The nature, scope, and characteristic features 35 of my invention will be more fully understood from the following description, taken in connection with the accompanying drawings, forming part hereof, in which—

Figure 1 is a top or plan view of the machine, illustrating the type-head, the manner of balancing and supporting the same, the driving mechanism therefor, and the means controlled by the driving mechanism for 40 shifting an inking-pad into and out of the path of the type-head embodying main features of my invention. Fig. 2 is a side elevational view of the machine, partly in section, illustrating the manner of connecting 45 the inking-pad holder with the machine, the means for adapting the same to inking-pads of varying sizes, the actuating mechanism for the inking-pad holder, and the adjustable and yielding table. Fig. 3 is a front elevational view illustrating the left-hand end of 50

the machine shown in Fig. 1. Fig. 4 is a detail view illustrating in side elevation the means for imparting an oscillatory movement to the type-head, and Fig. 5 is a detail view illustrating, partly in section and partly 60 in elevation, means for adjustably supporting the inking-pad in its holder.

Referring to the drawings, *a* is the bed-plate of the machine, which supports a standard or framework *a'*, preferably integral with the bed-plate *a*, as shown in Fig. 2. In bearings *a*² of the framework *a'* is located a shaft *b*, serving as the support for a type-head *c*, which, as shown in Figs. 2 and 3, is arranged beyond the framework *a'* and swings clear of the same. The type-head *c* in the present instance consists of a head *c'* proper, having numbering-wheels *c*², carried by a shaft or barrel *c*³, which head is supported by an arm *c*⁴, provided with a sleeve *c*⁵, through which 70 the end of the shaft *b* passes. A screw *b*' and washer *b*² prevent the disengagement of the sleeve *c*⁵ from the shaft *b*, but permits of the free turning of the sleeve *c*⁵ and its arm *c*⁴ on the shaft *b*. The arm *c*⁴ is provided with a counterweight *c*⁶, which by being properly 75 adjusted and clamped thereon by means of a set-screw *c*⁷ counterbalances the weight of the head *c'*. By the counterbalancing of the type-head *c* very little power is required to 80 oscillate the same upon its fulcrum point or shaft *b*, and at the same time the head *c* may be readily removed therefrom by the loosening of the screw *b*' to either rearrange the numbering-wheels *c*², to replace the same by 85 other printing means, or to place another type-head on the shaft *b*.

The preferred means for imparting an oscillatory movement to the type-head *c* is as follows: As shown in Fig. 1, the arm *c*⁴ of the type-head *c* is engaged by rollers *d*¹⁰, arranged on pins *d*', carried by a lever *d*, which lever by means of a roller *d*² engages the cam-groove *e*' of a cam-wheel *e*. The lever *d* is provided with a slot *d*³, through which 90 passes a bolt *f*. This bolt *f*, in conjunction with a disk or washer *f*', clamps the lever *d* to a headed bolt *f*², mounted in a bracket *b*³. The bolt *f*² is provided with an annular groove *f*³, engaged by the end of a set-screw *f*⁴ of the bracket *b*³, which permits of a free rotation of the bolt *f*² in the same. As shown 95 in Fig. 4, the cam-groove *e*' of the cam-wheel *e* is provided with two throws *e*² and *e*³, which when the cam-wheel is rotated imparts to the 100 105 110

lever d , by means of the pins d' and rollers d^{10} , an oscillatory movement to the arm c^4 of the type-head c . The throw e^2 of the cam-groove e' swings the type-head c into engagement with an inking-pad g and back into its normal position to permit the inking-pad g to be moved out of the path of the type-head c , after which the second throw e^3 , coming into engagement with the roller d^2 of the lever d , swings the type-head farther down upon a table h and upon an article placed thereon to imprint an impression onto the same. If the type-head c shown is replaced by another of either smaller or larger size or the head is required to vary the length of its oscillatory movements, this can be readily obtained by simply sliding the bracket b^3 backward or forward on the shaft b and the bolt f in the slot d^3 of the lever d until both the bracket b^3 and bolt f have been shifted into proper position, in which the same are held by the tightening of the bolt f and by the set-screw b^5 engaging the shaft b . The cam-wheel e is carried by a shaft e^4 , having its bearings in the framework a' , which receives its rotary movement from a shaft i by means of a worm i' and worm-gear e^5 , respectively, mounted on the shafts i and e^4 , as shown in Fig. 2. The shaft i , which is preferably carried by a partition-wall a^4 of the framework a' and by a bearing a^5 of the bed-plate a , is positively driven by a sheaf-wheel i^2 from any suitable source of power. (Not shown.) The inking-pad g , serving to ink the wheels c^2 of the type-head c prior to their engagement with an article placed upon the table h , consists, preferably, of a piece of felt g' or other absorbent material placed in a box g^2 . As shown in Figs. 1 and 2, the box g^2 is carried by a holder or bracket g^3 , which has a range of sliding movement parallel to the shaft b in a groove a^6 , arranged in the framework a' . The box g^2 , carrying the inking-pad g' proper, is supported in the bracket g^3 by adjusting-screws g^8 and is clamped thereto by means of a bar g^4 , the rods g^5 of which slide in eyes g^6 , arranged on the under side of the bracket g^3 , and are locked to the same by means of set-screws g^7 , as shown in Fig. 2. The box g^2 being supported by the adjusting-screws g^8 can be held by the same in varying angular positions in the bracket g^3 and can be raised and lowered therein. By this adjustment of the box g^2 the inking-pad g' thereof can be brought into required position when the extent of movement of the type-head c is increased or decreased, due to the adjustment of the fulcral point of the lever d , as hereinbefore described.

60 The preferred mechanism for shifting the inking-pad g below and away from the type-head c is as follows: To the shaft e^4 of the cam-wheel e is secured a cam k , provided with two throw portions k' and k^2 , which by being brought alternately into engagement with a

segment k^3 actuates the same and imparts to a shaft k^4 , connected therewith, a to-and-fro movement. This movement of the shaft k^4 by means of an arm k^5 and link k^6 is transmitted to the bracket g^3 of the inking-pad g , and the same is shifted alternately below and away from the type-head c' . When the inking-pad g is shifted below the type-head c' , the same is brought into engagement therewith by the throw portion e^2 of the cam-groove e' of the cam-wheel e to ink the numbering-wheels c^2 thereof. As soon as the wheels c^2 are inked the type-head c' is returned to its normal position by means of the cam-groove e' , after which the inking-pad is shifted backward into the position shown in Figs. 1 and 2. The throw portion e^3 of the cam-wheel e coming into engagement with the roller of the lever d swings the type-head c' downward onto the table h and brings the numbering-wheels c^2 into engagement with an article placed thereon. As shown in Figs. 2 and 3, the table h consists of a platen h' , which is connected with a bracket h^2 by means of bolts h^3 , sliding in openings arranged in the bracket h^2 . Surrounding the bolts h^3 and arranged between the platen h' and bracket h^2 are located springs h^4 , which support the platen h' and permit the same to yield when the type-head c' is brought into engagement with the article placed thereon. In order to permit of a proper imprint of the numbering-wheels c^2 when the article placed upon the platen h' is other than flat in shape and also to compensate for varying movements of the type-head c' , the bracket h^2 , supporting the platen h' by means of a bolt a^9 , is pivotally secured to a boss a^8 , preferably arranged integral with the bed-plate a .

I do not wish to be understood as limiting myself to all of the details of arrangement of the machine, as hereinbefore explained and as illustrated in the drawings, but,

Having thus described the nature and objects of my invention, what I claim as new, and desire to secure by Letters Patent, is—

1. In a machine of the character described, a head having printing means, a weight, means adapted to connect said head with said weight, means adapted to support said connecting means to permit said weight to balance said head, means engaging said connecting means adapted to impart to said head an oscillatory movement, and inking means adapted to permit of the inking of the printing means carried by said head.

2. In a machine of the character described, a head having printing means, a weight, means adapted to connect said head with said weight, means adapted to support said connecting means to permit said weight to balance said head, means engaging said connecting means adapted to impart to said head an oscillatory movement, inking means adapted to permit of the inking of the print-

ing means carried by said head, and means adapted to shift said inking means into and out of the path of said head.

3. In a machine of the character described, 5 a head having printing means, a weight, means adapted to connect said head with said weight, means adapted to detachably support said connecting means to permit said weight to balance said head, a table adapted to receive an article, inking means 10 adapted to ink the printing means carried by said head, and means adapted to bring said head and its printing means alternately into engagement with said inking means and the 15 article placed on said table.

4. In a machine of the character described, a head having printing means, a weight, means adapted to connect said head with said weight, means adapted to detachably support said connecting means and to permit said weight to balance said head, inking means adapted to be shifted alternately below and away from said head, an adjustable table, means adapted to actuate said head 25 by engaging said connecting means to bring the same and its printing means alternately into engagement with said inking means and said table, and means supporting a portion of said actuating means and adapted to permit of adjustment in the length of travel of 30 said head.

5. In a machine of the character described, a head having printing means, a weight, means adapted to connect said head with said weight, means adapted to detachably support said connecting means and to permit said weight to balance said head, means adapted to actuate said head by oscillating said connecting means, means supporting a 35 portion of said actuating means and adapted when adjusted to permit said portion to increase or decrease the length of oscillations of said head, inking means adapted to be shifted alternately below and away from 40 said head and its printing means, means adapted to raise and lower said inking means and to hold the same in varying angular positions with respect to said head, a table, means adapted to hold said table in varying 45 angular positions with respect to said head, said inking means and table arranged to be brought into their proper operative positions by the regulation of the length of travel of the said head.

55 6. In a machine of the character described, a head having printing means, an arm, a weight adjustably arranged on said arm and

adapted to counterbalance said head, a shaft adapted to detachably support said arm and head, inking means adapted to be shifted below and away from said head, a table, a lever adapted to engage said arm, and a cam adapted to oscillate said lever and by the same said arm and head to bring the same with its printing means alternately into engagement 65 with said inking means and table.

7. In a machine of the character described, a head having printing means, an arm, a weight adjustably arranged on said arm, a shaft adapted to detachably engage said arm 70 intermediate of said head and weight to permit the same to balance said head, an inking-pad, means adapted to hold and to shift said pad below and away from said head, means adapted to raise, lower and to hold said 75 pad in varying angular positions with respect to said head, a table, means adapted to hold said table in varying angular positions with respect to said head, a lever adapted to engage said arm, and a cam adapted to 80 oscillate said lever and by the same said arm and head to bring the head first into engagement with said pad and then with said table.

8. In a machine of the character described, a head having printing means, an arm, a weight adjustably arranged on said arm, a shaft adapted to detachably support said arm intermediate of said head and weight to permit the same to balance said head, a lever adapted to engage said arm, a double-throw 85 cam adapted to oscillate said lever and to impart to said head movements of varying length during a revolution of said cam, means supporting said lever and adapted when adjusted to permit of an increase or decrease in 90 the length of movement of said lever and head, an inking-pad, means adjustably supporting said inking-pad, an adjustable and yielding table, and means coöperating with said cam adapted to engage said inking-pad 95 holder to shift the inking-pad below said head to transmit ink to its printing means and to move the same out of the path of said head to permit the same to be brought into engagement with said table and the article 100 placed thereon.

In testimony whereof I have hereunto set my signature in the presence of two subscribing witnesses.

JAMES D. HUMPHREY.
